UNITED STATES PATENT OFFICE.

AUGUST KAMPFE, OF CLEVELAND, OHIO.

SAFETY DEVICE FOR ELEVATORS.

1,149,450.

Specification of Letters Patent. Patented Aug. 10, 1915.

Application filed December 24, 1914. Serial No. 878,267.

To all whom it may concern:

Be it known that I, AUGUST KAMPFE, a citizen of the United States, residing at Cleveland, in the county of Cuyahoga and State of Ohio, have invented certain new and useful Improvements in Safety Devices for Elevators, of which the following is a specification.

This invention pertains to safety devices for elevators, and the object of the invention is to provide three safety precautions which are mutually dependent and coöperate to protect an elevator against possible accident. To these ends, I provide means to automatically lock a door when the car is away from the landing either direction and to automatically unlock the same when at a landing; secondly, to automatically lock the car at the landing when the door is opened and to automatically unlock or release the car when the door is closed, and thirdly, to grip the operating cable when the door is opened and the car locked and to release the cable when the door is closed and the car unlocked to move in either direction. In the two latter movements, the door is the initial actuating medium while, in the first instance, the freedom of the door is dependent on the position of the car in respect to the landing.

In the accompanying drawings, Figure 1 is a relatively sectional elevation of a car and a door at a landing with the parts in the position seen in Figs. 2 and 3. Fig. 2 is a sectional elevation at right angles to Fig. 1. Fig. 3 is a horizontal view and Fig. 4 is an enlarged sectional elevation showing the door locking mechanism in locking position. Fig. 5 is a section of the latch and the recess or pocket inset in the door in which the latch engages.

As thus shown C represents the car, or a part thereof, and D the door. L is the landing and 2 the pivoted latch or dog by which the door is locked. The said latch is supported on a post or standard 3 from the landing and has an arm *a* adapted to rotate into and out of a specially provided pocket or recess 4 in the door, as seen especially in Fig. 4. The inner edge of said latch is circular or segmental and has a series of teeth or serrations adapted to be engaged by the spring-pressed shoe 5 on the car and by which the said latch is rotated out of the recess in the door when the car reaches the landing, thus releasing the door to be opened,

Fig. 1. The said latch is shown as having two opposite springs 6 connected therewith in such relation as to close the latch the instant the car starts from the landing and thus lock the door, and the shoe 5 is under a measure of spring pressure on its end supports 7 to accommodate itself to the fixed pivot of latch 2. The pivot of the latch 2 and the recess 4 therefor on the door are especially shown in section Fig. 5.

Now, as related to the door and the foregoing means for locking and unlocking the same automatically, I provide both a car lock and a cable lock which are jointly dependent on the door. That is, the door must be capable of movement when the car is at the landing and is provided with initial means for actuating the said locks, so that in the opening of the door both locks are automatically brought into engagement and when closed both locks are automatically disengaged. Thus, the door has a rack or series of teeth 8 on its bottom edge in engagement with a pinion 9 on the end of a rotatable shaft 10 and which terminates at the landing. The said shaft has a worm or thread 11 of long pitch in actuating engagement with a yoke 12 mounted thereon and controlling a thrust bolt 13 at each end. The said bolts are supported in suitable keepers in the landing and engage extension rods 14 having heads engaged by said bolts and adapted to be thrust endwise by the bolts in such measure as may be needed to bring the cable gripping or locking member 15 into engagement against the cable next beneath or at the V shaped stud 16, or its equivalent, the object in any event being to hold the cable temporarily against movement up or down by the operator in the car or, for that matter, by any one else.

Movement is conveyed from the said rods or extension bolts 14 to the said lock 15 through or by means of a cross-bar 17 which has sleeve supports 18 on its ends in which the extension bolts 14 have a threaded adjustment and support, and a stem 20 centrally on said cross bar 17 pivotally engages one end of a pivoted lever 21 while the other end thereof has a link 22 connecting it with a bell crank lever 23. A link 24 connects said lever with the lower end of the pivoted lock 15 for the cable. Spring S serves to reverse or open all said parts when the thrust by primary bolts 13 is relieved and the door is closed. Spirally wound springs

25 on the bolts 14 bear against the heads of said bolts at one end and against the ends of the cross-bar 17 at the other end in the said sleeves 18, and serve to communicate 5 the thrust from bolts 13 to said bar. When the thrust is withdrawn the springs 25 carry the bolts 14 back to starting position. The bar requires only a slight play to perform its function and this arrangement permits 10 the bolts to move a greater distance than the bar.

Thus it follows that when a landing has been made the door is automatically liberated to be opened and the opening thereof 15 automatically locks the elevator car and the cable. Then in order to move the car and to turn on the power the door must first be closed. This automatically releases both locks and the operation of the elevator proceeds otherwise as if no special safety mechanism were present.

What I claim is:

1. An elevator car, a landing door and an operating cable, in combination of mechanism for locking the car at a landing and the said cable simultaneously comprising a rack on the bottom of the said door, a worm screw in the landing and a yoke adapted to run on said screw, locking bolts engaged 25 with said yoke and adapted to penetrate the car, a pair of bolts on said car axially aligned with said locking bolts and a cross bar connecting the outer ends of said bolts, a lock 30 for said cable comprising a pivoted lever on the car and a stud fixed at the landing and actuating means for said lever connected initially with the said cross-bar.

2. An elevator car and means to prevent the operation of the operating cable when 35 the car is at a landing and the door is open,

said means comprising a screw located in the door landing and a yoke adapted to run thereon and a set of bolts engaged with said yoke and adapted to be thrust into the car, in combination with gripping means for the 45 cable consisting of a fixed stud at the landing, a lever pivoted between its ends on the car and adapted to press the cable against said stud, a pair of bolts in thrusting relations with said locking bolts, a cross-bar connecting the outer ends of said pair of bolts and a retracting spring for the said bar, and lever and link connections with said bar adapted to operate said locking lever.

3. An elevator having a car and an operating cable, in combination with a sliding door and means operatively connected therewith and adapted to lock the car at a landing and to grip the said cable simultaneously, said means comprising a pair of locking bolts supported in the landing and adapted to engage the car, a worm screw in the landing and a pinion thereon, a rack on the bottom of the door engaging said pinion, a yoke on said screw and engaged at its 65 ends with the heads of said bolts, a pair of auxiliary spring-pressed bolts engaged by said locking bolts and a cross bar connecting the same, a locking lever for the cable and means to actuate the said lever having 70 operating connection with said cross bar, whereby both the car and the cable are simultaneously locked.

In testimony whereof I affix my signature in presence of two witnesses.

AUGUST KAMPFE.
